UNITED STATES PATENT OFFICE

CARMINE A. GRIECO, OF BROOKLYN, NEW YORK, ASSIGNOR OF ONE-FOURTH TO THOMAS PETRY, ONE-FOURTH TO FRANCESCO A. GRIECO, AND ONE-FOURTH TO DOMENICO VESSA, ALL OF BROOKLYN, NEW YORK.

AUTOMATIC PISTOL.

1,202,707.

Specification of Letters Patent. Patented Oct. 24, 1916.

Application filed July 1, 1916. Serial No. 107,060.

To all whom it may concern:

Be it known that I, CARMINE A. GRIECO, a citizen of the United States, residing at Brooklyn, in the county of Kings and State of New York, have invented certain new and useful Improvements in Automatic Pistols; and I do hereby declare the following to be a full, clear, and exact description of the invention, such as will enable others skilled in the art to which it appertains to make and use the same.

This invention has for its object to provide an improved fire arm including a novel cartridge holder or magazine supported in the pistol handle and having two chambers each adapted to receive a supply of cartridges, whereby the cartridge capacity of pistols of this type is practically doubled.

Another object is the provision of means for controlling the projection of the cartridges from the two cartridge chambers to the firing chambers.

With these and other objects in view, the invention consists in the novel construction, combination and arrangement of parts as will be hereinafter specifically described, claimed and illustrated in the accompanying drawings, in which:

Figure 1 represents a side elevation of the improved fire arm, Fig. 2 represents a bottom plan view thereof, Fig. 3 represents a longitudinal sectional view through the pistol, Fig. 4 represents a sectional view through the double cartridge holder or magazine removed from the handle of the pistol, Fig. 5 represents a front elevation of the barrel of the pistol, Fig. 6 represents a longitudinal sectional view on the line 6—6 of Fig. 3, and Fig. 7 represents a transverse sectional view on the line 7—7 of Fig. 3.

Referring to the drawings in detail, wherein similar reference numerals designate corresponding parts throughout the several views, the numeral 10 indicates the body of the pistol, which includes the trigger guard, hollow handle 11 and integral upstanding block 12. A pivot pin 13 is inserted through the forward extremity of the body 10 and pivotally connects the forward portion of the barrel 14 therewith, the rear terminal of the barrel being detachably connected with the upstanding block 12 by a detachable pin or bolt 15. The barrel 14 is formed with two longitudinal bores 16 and

a spring-receiving opening 17 arranged centrally above and parallel to the bores 16.

The bolt of the pistol includes the breech block 18 slidably mounted in the chamber 19 in the body 10 rearwardly of the barrel 14 and connected with a substantially U-shaped guide member 20 slidably mounted upon the body 10.

The bolt 18 is normally retained in engagement with the rear terminal of the barrel 14 by the tension of an expansible spring 21 arranged in the chamber 17 and confined between a shoulder 22 and the head 23 of a rod 24, pivotally connected at 25 with the sliding bolt 18. A pivoted locking member 24^a is mounted in a recess formed in the bolt 18 and is adapted to engage in a recess formed in the rearwardly extending portion of the barrel 14 to lock the bolt against operation. The locking member 24^a may be conveniently operated by the user by means of a button 26 carried by the sliding guide 20 of the breech bolt 18.

The bolt 18 is provided with two spaced firing pins 27 arranged in alignment with the bores 16 and normally retained in rearwardly extended position by the tension of springs 28.

The hammer mechanism comprises a pair of hammers 30, pivotally mounted at 31 in the upper and rear portion of the hollow handle 11, which are adapted to be automatically set in the usual manner by the recoil movement of the bolt 18. Each hammer 30 is connected by a link 32 with one of a pair of rods 33, slidably mounted in a chamber 34 formed in the lower portion of the handle 11. When released, the hammers 30 are automatically thrown forwardly against the rear terminals of the firing pins 27 by the tension of springs 35 confined in the chambers 34 between the heads 36 of the rods 33 and shoulders 37 formed internally of the chambers 34. The lower terminals of the chambers 34 are normally closed by removable plugs 38.

The upper edge portions of the hammers 30 are concaved, as indicated at 39, and adapted to engage a shaft or bolt 40, non-rotatably and slidably mounted in the rear portion of the body 10 and having a slot 41 formed centrally therein of such width as to permit either of the hammers 30 to move therethrough. By the provision of the shaft

40 with a single recess 41 therein, one of the hammers 30 is always held in inoperative position. However, either one of the hammers may be released, for operation, by so 5 adjusting the shaft 40 as to swing rearwardly and downwardly through the recess 41.

The spring actuated trigger 43 is connected with the body 10 and is adapted to actuate the sear 44 mounted in the handle 11 and normally retained in engagement with the rod 33 by the tension of a leaf spring 45 confined in the handle 11. The tooth of the sear 44 is adapted to engage in a recess 15 of the rod 33 to lock the latter in elevated position against action of the spring 35. The trigger 43 may be locked against operation by a trigger safety lock 47 mounted in the body 10 rearwardly of the trigger 43.

20 The magazine, or cartridge holder, illustrated in detail in Fig. 4 comprises a body 48 having two cartridge-receiving chambers 49 therein in which is received a supply of cartridges 50^a, which are normally pressed 25 upwardly within the holder 48 by the tension of springs 51^a. The holder 48 is adapted for insertion in the hollow handle 11, in the usual manner, and is locked in position in the handle by a catch 52^a. The projection 30 of the cartridges 50^a from either chamber of the holder 48 to the corresponding bore 16 of the double barrel is controlled by stop plates 50, slidably mounted in slots 51 formed in the opposite sides of the body 10 and connected with buttons 52, arranged exteriorly of the body whereby the plates 50 may be conveniently operated to permit the cartridges in either chamber to feed into the proper bore 16.

40 In use, the shaft 40 is adjusted so as to release the right hand hammer 30 and the cartridge holder 48 having a supply of cartridges 50^a in each chamber 49 is inserted in the handle 11. The breech bolt 18 and 45 guide member 20 are subsequently moved rearwardly, thereby setting the hammer 30, which is locked by the sear 44. The stop plate 50 at the left side of the pistol is adjusted so as to prevent the projection of the 50 cartridges contained therein into the left hand bore 16 and thus by actuating the trigger 43 the cartridges in the right hand chamber of the cartridge holder 48 are successively fired.

55 When the supply of cartridges in the right hand chamber of the holder 48 is exhausted, the shaft 40 is moved to the left, subsequent to move the breech bolt 18 and guide member 20 rearwardly, thus permitting the left 60 hand hammer 30 to move freely through the recess 41 and lock the right hammer 30 in inoperative position. The left hand stop plate 50 is subsequently adjusted so as to permit the projection of the cartridges into 65 the left hand bore 6 of the barrel.

What I claim is:

1. In an automatic pistol, a body and a handle carried thereby, a barrel connected with said body and having two parallel bores, a cartridge holder removably positioned in said handle having two cartridge-receiving chambers arranged side by side, a bolt slidably mounted in the rear portion of said barrel, firing pins carried by said bolt arranged in line with said bores, and a hammer mechanism associated with said bolt. 70

2. In an automatic pistol, a body and a hollow handle formed integral therewith, a barrel pivotally secured to said body having spaced parallel bores, and a chamber connecting the rear terminals of said bores, a breech bolt slidably mounted in the chamber, and firing pins mounted in said breech bolt and arranged in line with the bores. 80

3. In an automatic pistol, a body and a hollow handle formed integral therewith, a barrel connected with said body having spaced longitudinal bores and a chamber connecting the rear terminals of said bores, a breech bolt slidably mounted in the said chamber, firing pins supported in said breech bolt and arranged in line with said bores, and a pivoted hammer adapted to actuate each firing pin. 85

4. In an automatic pistol, a body and a hollow handle formed integral therewith, a barrel connected with said body having two spaced bores and a chamber connecting the rear terminals of said bores, a breech bolt slidably mounted in said chamber, firing pins supported in said breech bolt and arranged in line with said bores, a pivoted hammer associated with each firing pin, and means for locking said hammers in inoperative position. 95

5. In an automatic pistol, a body and a hollow handle formed integral therewith, a barrel connected with said body having two spaced bores and a chamber connecting the rear terminals of said bores, a breech bolt slidably mounted in said chamber, firing pins supported in said breech bolt and arranged in line with said bores, a pivoted hammer associated with each firing pin, and means for alternatively locking said hammers in inoperative position. 110

6. In an automatic pistol, a body, a hollow handle carried thereby, a barrel connected with said body having spaced parallel bores and a chamber connecting the rear terminals of said bores, a breech bolt slidably mounted in said chamber, firing pins supported in said bolt and arranged in line with said bores, independently operable hammers adapted to actuate said firing pins, and means for alternately locking said hammers in inoperative position. 120

7. In an automatic pistol, a body and a hollow handle formed integral therewith, a barrel connected with said body having 130

- spaced parallel bores, and a chamber connecting the rear terminals of said bores, a breech bolt slidably mounted in said chamber, a cartridge holder removably positioned in said handle having two cartridge-receiving chambers arranged side by side adapted to receive cartridges for projection into the respective bores, firing pins mounted in said breech bolt and arranged in line with said bores, independently operable hammers pivotally mounted in said body and adapted to actuate the firing pins, and means for alternately locking the hammers in inoperative position. 5
- 10 8. In an automatic pistol, a body and a hollow handle connected therewith, a barrel connected with said body having spaced parallel bores, and a chamber connecting the rear terminals of said bores, a breech bolt slidably mounted in said chamber and a cartridge holder removably positioned in said handle having two cartridge-receiving chambers arranged side by side. 20
- 15 9. In an automatic pistol, a body and a hollow handle connected therewith, a barrel connected with said body having spaced parallel bores, and a chamber connecting the rear terminals of said bores, a breech bolt slidably mounted in said chamber, a cartridge holder removably positioned in said handle having two cartridge-receiving chambers arranged side by side. 25
- 20 10. In an automatic pistol, a body and a hollow handle connected therewith, a barrel connected with said body having spaced parallel bores, and a chamber connecting the rear terminals of said bores, a breech bolt slidably mounted in said chamber, a cartridge holder removably positioned in said handle having two cartridge-receiving chambers arranged side by side adapted to receive cartridges for projection into the respective bores, and means for controlling the projection of the cartridges into the bores. 30
- 25 11. In an automatic pistol, a body and a hollow handle formed integral therewith, a barrel connected with said body having spaced parallel bores, and a chamber connecting the rear terminals of said bores, a breech bolt slidably mounted in said chamber, a cartridge holder removably positioned in said handle having two cartridge-receiving chambers arranged side by side and adapted to receive cartridges for projection into the respective bores, and independently operable means associated with each cartridge-receiving chamber for preventing projection of the cartridges from the chambers to the respective bores. 35
- 30 12. In an automatic pistol, a body and a hollow handle connected therewith, a barrel connected with said body having spaced parallel bores, and a chamber connecting the rear terminals of said bores, a breech bolt slidably mounted in said chamber, a cartridge holder removably positioned in said handle having two cartridge-receiving chambers arranged side by side adapted to receive cartridges for projection into the respective bores, means for controlling the projection of the cartridges from the cartridge-receiving chambers to the bores, firing pins mounted in said breech bolt and arranged in line with said bores, independently operable hammers pivotally mounted in said body and adapted to actuate the firing pins, and means for alternately locking the hammers in inoperative position. 40
- 35 13. In an automatic pistol, a body and a hollow handle connected therewith, a barrel connected with said body having spaced parallel bores, and a chamber connecting the rear terminals of said bores, a breech bolt slidably mounted in said chamber, a cartridge holder removably positioned in said handle having two cartridge-receiving chambers arranged side by side and adapted to receive cartridges for projection into the respective bores, and independently operable means associated with each cartridge-receiving chamber for preventing projection of the cartridges from the chambers to the respective bores. 45
- 40 14. In an automatic pistol, a body and a hollow handle connected therewith, a barrel connected with said body having spaced parallel bores, and a chamber connecting the rear terminals of said bores, a breech bolt slidably mounted in said chamber, a cartridge holder removably positioned in said handle having two cartridge-receiving chambers arranged side by side and adapted to receive cartridges for projection into the respective bores, and independently operable means associated with each cartridge-receiving chamber for preventing projection of the cartridges from the chambers to the respective bores. 50
- 45 15. In an automatic pistol, a body and a hollow handle connected therewith, a barrel connected with said body having spaced parallel bores, and a chamber connecting the rear terminals of said bores, a breech bolt slidably mounted in said chamber, a cartridge holder removably positioned in said handle having two cartridge-receiving chambers arranged side by side and adapted to receive cartridges for projection into the respective bores, and independently operable means associated with each cartridge-receiving chamber for preventing projection of the cartridges from the chambers to the respective bores. 55
- 50 16. In an automatic pistol, a body and a hollow handle connected therewith, a barrel connected with said body having spaced parallel bores, and a chamber connecting the rear terminals of said bores, a breech bolt slidably mounted in said chamber, a cartridge holder removably positioned in said handle having two cartridge-receiving chambers arranged side by side and adapted to receive cartridges for projection into the respective bores, and independently operable means associated with each cartridge-receiving chamber for preventing projection of the cartridges from the chambers to the respective bores. 60
- 55 17. In an automatic pistol, a body and a hollow handle connected therewith, a barrel connected with said body having spaced parallel bores, and a chamber connecting the rear terminals of said bores, a breech bolt slidably mounted in said chamber, a cartridge holder removably positioned in said handle having two cartridge-receiving chambers arranged side by side and adapted to receive cartridges for projection into the respective bores, and independently operable means associated with each cartridge-receiving chamber for preventing projection of the cartridges from the chambers to the respective bores. 65
- 60 18. In an automatic pistol, a body and a hollow handle connected therewith, a barrel connected with said body having spaced parallel bores, and a chamber connecting the rear terminals of said bores, a breech bolt slidably mounted in said chamber, a cartridge holder removably positioned in said handle having two cartridge-receiving chambers arranged side by side and adapted to receive cartridges for projection into the respective bores, and independently operable means associated with each cartridge-receiving chamber for preventing projection of the cartridges from the chambers to the respective bores. 70

In testimony whereof I affix my signature in presence of two witnesses.

CARMINE A. GRIECO.
